(57) **CLAIM**

The ornamental design for a power outlet with USB port, as shown and described.

DESCRIPTION

FIG. 1 is a front perspective view of a power outlet with USB port, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof, wherein the broken lines showing the power cord with a plug are included for illustrative purposes only and form no part of the claimed design.
